(57) **CLAIM**

The ornamental design for a lifting harness for dog, as shown and described.

DESCRIPTION

FIG. 1 is a front perspective view of a lifting harness for dog, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of detail “9”, identified in FIG. 1; and,

FIG. 10 is an enlarged view of detail “10”, identified in FIG. 2.

The dot-dash broken lines in FIGS. 1, 2, 9 and 10 are used to show an area of enlargement and with the broken lines forming no part of the claimed design.

1 Claim, 10 Drawing Sheets
